ATTY.

UNITED STATES PATENT OFFICE.

JOHN P. EUSTIS, OF NEWTONVILLE, MASSACHUSETTS.

BATH-TUB SEAT.

SPECIFICATION forming part of Letters Patent No. 764,232, dated July 5, 1904.

Application filed March 9, 1904. Serial No. 197,352. (No model.)

To all whom it may concern.

Be it known that I, JOHN P. EUSTIS, a citizen of the United States, residing at Newtonville, in the county of Middlesex and State of Massachusetts, have invented certain new and useful Improvements in Bath-Tub Seats, of which the following is a specification, reference being had therein to the accompanying drawings.

10 Figure 1 is a lengthwise central section of my improved bath-tub seat complete at line 2 2 of Fig. 2. Fig. 2 is a top plan view, and Fig. 3 is an under plan view, of the complete seat. Fig. 4 is an under plan view of my new form of bent-rod hanger detached from the seat, the dotted lines indicating outward instead of inward relative inclination of the arms. Fig. 5 is an enlarged view of a portion of the hanger-bracket and shows the 15 points at which the hanger-arms telescopically contact with the open-ended tubular portions of the bracket. Fig. 6 is a plan view of a sheet-metal blank, showing the lines of cut requisite to produce a plurality of brackets forming blanks from a sheet of metal without waste of stock.

Bath-tub seats when used are suspended from the upper margins of bath-tubs and are subjected to a considerable variety of strains 20 occasioned by persons moving when sitting on the seats. The seats must be made strong for safety, light for convenience, and have hangers which are adjustable, so as to fit tubs of varying widths.

35 The object of my invention is to produce strong, durable, and readily-adjustable bath-seats which are strong enough to be safe and light enough to be conveniently handled.

In the drawings, 1 is the hanger-receiving bracket, which is formed with two parallel integral open-ended tubular portions 2, within which the arms of the hanger are telescopically received and adjustable.

3 represents lobes, preferably at the inner 45 ends of the brackets and bored for the reception of screws 4, which enter the seat-board A and clamp the inner ends of the brackets tight to the under side of the board, while the integral hook extension 5 passes over the 50 end of the seat-board and hooks tightly on

the upper margin of the seat-board. The bracket-hook 5 and the screws 4 coöperate to bind the hanger-bracket firmly in place and to prevent twisting of the hanger-bracket on the seat-board, at the same time binding the 55 inner ends of the brackets snugly to the under side of the seat-board.

The hangers 6 are conveniently formed of metallic rods and according to my invention are formed with arms 7 7 of lesser diameter 60 than the interior diameter of the tubular portions 2 of the bracket, so that the arms 7 7 may be readily entered and adjusted in the tubular portions 2 2 of the hanger-brackets; but these hanger-arms 7 7 are when the 65 hanger is detached, at an inclination one to the other in process of production being set in an inclined position, one in relation to another, as shown, for example, in Fig. 4, and it is only by moving the arms 7 7 laterally 70 against the resiliency of the intermediate portion of a hanger that the arms 7 7 can be entered in the tubular portions 2 2 of the bracket whatever the relative inclination of the arms one in relation to the other may be. 75

When a hanger and bracket are assembled, the bracket-arms 7 7 spring apart and pass diagonally through the tubular portions 2 2 of the bracket. In consequence of the diagonal passage of the arms 7 7 through the parallel tubular portions or hanger-receiving tubes 2 2 of the bracket the only points of contact between the bracket-arms and inner surfaces of the tubular portions 2 2 are at opposite end portions of the tubular parts 2 2 at 8 85 and 9 9, except, however, that there is a line of continuous contact between the upper side of each hanger-arm 7 and the opposed inner surface of the tubular portions 2 2, as indicated at 10 10. By this construction, while 90 a telescopic connection is obtained between the hanger-arms 7 7 and the tubular portions 2 2 of the hanger-receiving bracket, the points of contact between the arms 7 7 and inner surfaces of the tubular portions 2 2 are minimized, 95 and this is important to prevent such rusting together of the opposed parts as will seriously interfere with the adjustability of the hangers in relation to the brackets.

In manufacturing seats embodying my in- 100

vention it becomes unnecessary to go to the expense of boring two holes in each end of the seat-board, an operation that is attended with peculiar difficulties and expense; and I find that by using sheet-metal plates of proper dimensions and cutting the flatsheet on the lines w the sheet may be cut into a plurality of bracket-forming blanks Y without waste of stock, the lobes 3 being perforated and the tube-forming portions w' being rolled to form the hanger-receiving tubes 2 of the finished bracket, and the hook-forming lobe w^2 being bent to form the hook 5 of the finished bracket. The bracket is readily produced without waste of stock and at a low cost of manufacture.

What I claim is—

1. In a bath-tub seat, the combination of a seat-board; a hanger-bracket at each end thereof; fasteners for securing the brackets to the seat-board; and a hanger for each bracket;

each bracket having a hooked end which laps over an end of the seat-board and also having, on the under side of the seat-board, a pair of hanger-receiving tubes; the hangers being formed with arms which are inclined, one in relation to the other, and telescopically enter said tubes wherein the arms are partially out of contact with the inner walls of the tubes. 25

2. As a new article of manufacture, the herein-described sheet-metal, bracket-forming blank having a hook-forming lobe at one of its ends, and a pair of tube-forming portions at a distance from said lobe and at opposite sides of the blank. 30

In testimony whereof I affix my signature in presence of two witnesses.

JOHN P. EUSTIS.
